UNITED STATES PATENT OFFICE.

OSCAR KIESSIG, OF DALLAS, TEXAS.

AIR REGULATING ATTACHMENT.

1,301,455.

Specification of Letters Patent. Patented Apr. 22, 1919.

Application filed April 30, 1918. Serial No. 231,701.

To all whom it may concern:

Be it known that I, OSCAR KIESSIG, a citizen of the United States, residing at Dallas, in the county of Dallas and State of Texas, 5 have invented certain new and useful Improvements in Air-Regulating Attachments, of which the following is a specification.

This invention relates to new and useful improvements in air regulating attachments 10 for carbureters.

Some types of carbureters have an air inlet which is controlled only by a valve which is mechanically operated in unison with a throttle valve. The suction created by the 15 engine has no effect upon the air supply and there is no corresponding control of the air supply except that which is had by a mechanical adjustment of the air valve.

Various attachments have been made 20 which provide a valve in addition to the usual air valve and which is operated by the suction created by the engine. These attachments have been more or less complicated or possessed of objectionable features.

25 The purpose of this invention is to combine all the good points of the devices which have gone before and produce a device which will be simple in construction and inexpensive to manufacture.

30 In carrying out the invention a sleeve or housing is provided and constructed to be mounted at the air inlet of the carbureter. This sleeve is provided with a hinged valve normally closing the sleeve transversely and 35 held in this position under light spring tension. The valve is mounted on a transverse shaft and is provided with an arm connected with a coiled spring in such a way that the valve may swing in opposite directions.

40 The valve being swung inward by the suction created by the engine and permitted to swing backward when subjected to back pressure where the engine back fires. The spring is connected with the valve so that 45 when said valve is swung in one direction the end of the spring is carried above the pivot point and when said valve is swung in the other direction the spring is carried below the pivot point.

50 The invention will be more readily understood from a reading of the following specification and by reference to the accompanying drawings, in which an example of the invention is illustrated, and wherein—

55 Figure 1 is a view of a carbureter with a heating pipe attached and equipped with an

attachment constructed in accordance with this invention,

Fig. 2 is a longitudinal sectional view of the attachment, and 60

Fig. 3 is a transverse sectional view on the line 3—3 of Fig. 1.

In the drawings the numeral 1 designates a carbureter having an air inlet 2. At the air inlet a hot air pipe 3 is connected in the 65 usual manner.

The invention includes an attachment in the form of a sleeve or housing 4 having its outer end 5 flared. This sleeve fits snugly in the lower end of the pipe 3, the 70 flared end 5 limiting its insertion by engaging with the edge of the pipe as shown.

At the inner end of the sleeve a disk valve 6 is transversely hinged on a shaft 7 having its ends secured in the sleeve. The valve is 75 provided with a pair of upset ears 8 through which the shaft passes and whereby the valve is mounted on the shaft. The shaft extends across the lower portion of the valve which has the greater portion of its area 80 above said shaft.

From the lower end and center of the valve an arm 9 is bent upward at an acute angle to the valve and terminates in an outwardly bent eye 10 which is substantially at 85 the same elevation as the shaft 7. One end of a light coiled spring 11 is engaged in the eye and the other end is attached to a lug 12 at the portion 5 of the sleeve.

By observing Fig. 2 it will be seen that 90 the tension of the spring is exerted so as to hold the valve substantially balanced and transversely of the sleeve. However, as indicated by the dotted lines the valve may be swung in either direction. When it is 95 swung into the sleeve under the influence of the suction created by the engine the arm 9 is swung downward and the spring 11 extended so that as soon as the suction is relieved the spring swings the valve back to 100 its normal position. Should the engine back fire the back pressure created will strike the valve 6 and swing it outward whereby the eye 10 will be carried above the shaft 7, but the valve returned to its normal position as 105 soon as the pressure is released. The operation of this valve is well understood and it is deemed unnecessary to enter into a description of the same.

It will be seen that the attachment comprises a few number of parts and owing to its simplicity can be cheaply made. The

arm 9, eye 10 and ears 8 are all formed up from the plate which forms the valve. The shaft and the spring are the only other parts which are placed in the sleeve. One of the features which reduces the cost of manufacture is the fact that the valve does not have to be adjusted after the attachment is assembled. There is but one spring and it may vary in tension without affecting the normal adjustment of the valve. Where two springs are used it is evident they must be adjusted in harmony.

What I claim; is,

1. In an air regulating attachment for carbureters, a sleeve adapted to be mounted at the air inlet of a carbureter, a disk valve hinged transversely of the sleeve, said valve having a transverse axis, and a coiled spring

mounted within the sleeve and having one end attached to the sleeve and the other end attached to the valve at substantially the same elevation as that of the transverse axis.

2. In an air regulating attachment for carbureters, a sleeve adapted to be mounted at the air inlet of a carbureter, a disk valve, a transverse shaft mounted in the sleeve and on which the valve is mounted, an arm bent upward from the valve below the shaft and having its upper end terminating adjacent the shaft, a coiled spring within the sleeve having one end attached thereto and the other end attached to the upper end of said arm.

In testimony whereof I affix my signature. 35
OSCAR KIESSIG.
